UNITED STATES PATENT OFFICE.

GEORGE C. CUMMINGS, OF ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed June 30, 1924. Serial No. 723,142.

To all whom it may concern:

Be it known that I, GEORGE C. CUMMINGS, a subject of the King of Great Britain, residing at Orange, in the county of Essex, 5 State of New Jersey, have invented certain new and useful Improvements in Telegraph Systems, of which the following is a full, clear, concise, and exact description.

This invention relates to duplex telegraph systems.

The invention may be arranged for duplex operation, that is, transmission in both directions simultaneously, but preferably it is adapted to half-duplex operation in which 15 the impulses are transmitted one way at a time. Heretofore, in operating metallic circuit systems half-duplex, it has been the practice to operate the loop circuit as a balanced duplex which does not readily lend 20 itself to the connection of three or more circuits to operate half-duplex in several directions out of one office. In the use of such systems in which the transmission of the impulses results from the application of 25 currents of positive and negative polarity, considerable difficulty has been experienced when the system is utilized with a number of 30 way-stations. With this type of system a number of relays are necessarily connected in series, and, in consequence, considerable 35 inductive discharge through the balancing network results, which is sufficient to destroy the relay adjustment. It is therefore necessary, when it is desired to receive or transmit, to change the adjustment of the relays 40 to correct for this unbalanced condition in order to receive and transmit correct signals.

It is the object of the present invention to obviate the difficulties heretofore encountered 45 by arranging the system to cause the transmission of current reversals on the metallic circuit, while in the case of the loop circuit the circuit is actually opened and closed.

According to the preferred form, the invention provides a metallic line circuit equipped with what is commonly referred 50 to as a "vibrating relay" operating to impress impulses of both polarities on a local circuit. Connected in this local circuit and responsive to the positive and negative current impulses, is a relay which functions to make and break the loop circuit, whereby 55 the signals received from the line will be retransmitted to the station connected there-

to. By having other relays connected in the local circuit but arranged to be unresponsive to the operation of the vibrating relay, impulses may be transmitted from the loop circuit to the metallic line circuit, and thence 60 to the connected stations.

A better understanding of the invention may be had from the following description, taken in conjunction with the accompanying drawing, in which one embodiment of the 65 invention is illustrated.

In the single figure of the drawing, a pair of line conductors 5—6 constituting a metallic line circuit terminate at a station in the 70 windings of a vibrating relay 7, which are in turn connected to the respective terminals of an artificial line and which form the arms of a duplex bridge. The vibrating relay 7 comprises operating windings 8 and 9, and opposing and accelerating windings 10. 75 This type of relay is commonly referred to as the "Gulstad vibrating relay," and is also arranged with a condenser 11 and resistance 12. When the armature of this relay engages either of its opposing contacts, a circuit is established for charging the condenser 11 in a direction depending upon the polarity of the current applied through the engaged contact. Normally, the current in the 80 main line winding is opposed by the current in the opposing winding so that the magnetic effect produced by either of these windings predominates. In other words, the magnetic effect of one is partly neutralized by the other. However, upon the reception 85 of a signal, the current in the opposing winding predominates in which case the armature is caused to move from the engaged contact. The instant the armature moves from the engaged contact, the charge on the 90 condenser 11, resulting from the engagement of the armature with the previously engaged contact, discharges through the accelerating winding 10 and the resistance 12 to ground. The movement of the armature is thereby 95 accelerated to its opposite contact, after which a circuit is established for causing the condenser to assume a charge in accordance with the polarity of the source of current applied through the then engaged contact. 100

The armature of the vibrating relay 7 is connected to a local circuit in which there is included a plurality of relays, namely, a loop control relay 18, a break relay 19 and a pole changing or sending relay 20. For 105 110

monitoring purposes there is also connected in this local circuit a polarized sounder 15 which responds to the reversals of the armature of the vibrating relay 7 for recording the signals repeated to the local circuit.

In order to regulate the current in the local circuit, resistances 16 and 17 are arranged to form a potentiometer so that when the armature of the vibrating relay 7 engages its contacts, currents of predetermined values will flow in the local circuit for producing effects which will later be described. Each of the relays 19 and 20 has a winding connected to the circuit including a resistance 23, which functions to electrically bias these relays. The purpose of providing this biasing arrangement is to correct for differences in ground potentials. However, the relays could be equipped with mechanical means for accomplishing the same purpose.

Extending from the contact of the loop control relay 18 is a loop circuit 24, which has connected therein a sounder 25 and a transmitting key 26.

In order to permit the connection of several stations which are provided with the same equipment and which desire to receive the same messages transmitted over the metallic circuit 5, 6, the loop circuit terminates in a pair of jacks 28 and 29. Duplicate equipment, represented by the rectangle 30, may be connected with the loop circuit by the insertion of the plugs 31 and 32 in their respective jacks. By completing the connection of these plugs with their respective jacks, the continuity of the circuit is extended to include the duplicate equipment 30, which is located at a different station. Similarly, other stations could be connected to the metallic circuit.

The operation of the system will now be described. Assume, for the sake of illustration, that impulses are being impressed at the distant end of the metallic circuit 5, 6. These impulses, upon being received, pass through the main line windings 8 and 9 to the artificial line AL. The effect of these currents is such as to produce a magnetic effect which predominates over that produced by the opposing winding 10, and in consequence the armature of the relay 7 is caused to disengage the uppermost contact. Accordingly, the condenser 11, which was previously charged negatively, discharges through the winding 10 and the resistance 12 to ground, and accelerates the movement of the armature to its positive contact. When the armature of the relay 7 is in engagement with its negative contact, current flows from the source of current connected with the resistance 17, through this resistance 17, resistance 16, armature and upper contact of the relay 7 to the negative pole of the source of current. Also, current flows through the windings of the relays 18, 19

and 20. It should be noted here that the windings of relays 19 and 20, which are traversed by current from the sources impressed due to the operation of the relay 7, are in a direction such as to produce a magnetic effect which tends to maintain the armatures of these relays open, but in the case of the relay 18 the magnetic effect produced is such as to maintain its contact closed, or the position shown in the drawing. The relays 19 and 20 are, however, prevented from maintaining their contacts open when the armature of the relay 7 is engaged with the negative pole of battery because of the current flowing from the battery 34, contact of the jack 29, key 26, sounder 25, loop circuit 24, contact and armature of relay 18, right hand windings of relays 19 and 20, contact of jack 28 to the negative pole of the battery. The current flowing in the circuit just traced produces a magnetic effect which predominates over that produced by the current flowing in the circuit including the left hand windings of the relays 19 and 20, whereby these relays are prevented from maintaining their contacts open so that in consequence the contacts remain in the position shown. Upon the reversal of the armature of relay 7 and the engagement thereof with the contact connected with the positive pole of the battery, the current in the circuit including the windings of the relays 18, 19 and 20 reverses and is increased to a value such as to cause the movement of the armature of the relay 18. The current through the windings of the relays 19 and 20 is, however, in a direction to aid the current flowing from the battery 34 through the right hand windings of these relays, and their armatures therefore remain in the position shown in the drawing. Due to the operation of the relay 18, the loop circuit 24 is opened and impulses are repeated therein for causing the operation of the sounder 25.

The contacts of the relay 18 are bridged with a condenser 21 and a resistance 22 for nullifying the detrimental sparking effect produced upon the opening and closure of the contact of this relay. Likewise, the contacts of the relay 7 may be bridged with a condenser and resistance for absorbing the sparking produced upon the operation of its armature. The use of a condenser and resistance in this manner not only eliminates to a considerable degree the sparking, but also tends to stabilize the balance, thereby creating more satisfactory operating conditions.

Should the key 26 be opened slightly ahead of the disengagement of the armature of relay 7 with the contact associated with the negative pole of the battery, or be opened simultaneously therewith, the loop circuit will be opened and the current flowing

through the left hand windings of the relays 19 and 20 will be sufficient to cause the reversal of their armatures or to assume a position opposite to that shown in the drawing. The relay 19, in operating, short circuits the contacts of the relay 18 and extends the loop circuit through to the relay 20, thereby permitting the control of this relay from the key 26. Now, should the relay 18 operate, the loop circuit will be closed irrespective of its operation through the contact and armature of relay 19. The reversal of the armature of relay 20 impresses on the circuit 35 an impulse of a positive polarity, which, upon being received at the distant station or the station to which the metallic circuit 5, 6 extends, will constitute a break signal, indicating to the operator thereat that the party on the loop circuit desires to reverse the direction of sending. In this same manner, when it is desired to transmit by the operation of the key 26 which opens and closes the loop circuit 24, the pole changing relay 20 will follow the movement of the key 26 for transmitting over the metallic circuit 5, 6 impulses of positive and negative polarity.

It is seen from the previous description that should the key 26 be operated for transmitting a break signal simultaneously with the operation of the vibrating relay 7, due to an incoming impulse, the loop circuit will not be left open, thereby preventing the operator on the loop circuit from gaining control of the circuit, this being accomplished by the provision of the relay 19, which short circuits the contacts of the relay 18 and extends the loop circuit to the windings of these relays.

Although the invention has been disclosed and described with reference to a particular system, it is of course obvious that various departures and modifications may be made without departing from the spirit and scope of the invention.

What is claimed is:

1. In a telegraph system, a metallic circuit, a local circuit, signal responsive means connected in said metallic circuit for impressing on said local circuit positive and negative impulses, a loop circuit, means included in said local circuit for repeating to the loop circuit open and closed circuit conditions in accordance with the positive and negative current impulses impressed on said local circuit by said signal responsive means, and a sending relay in said local circuit.

2. In a telegraph system, a signaling path, a local circuit, a vibrating relay responsive to reversals of current impulses impressed on said signaling path for applying corresponding impulses to said local circuit, a loop circuit, means included in said local circuit for opening and closing said loop circuit in accordance with reversals of impulses im-

pressed on said local circuit, and a relay in said local circuit for sending signals over said path.

3. In a polarized duplex telegraph system, a signaling path, an electro-responsive device connected in said signaling path and responsive to reversals of signal currents for repeating corresponding signals to a local circuit, a loop circuit, means responsive to the reversals of current in said local circuit for making and breaking said loop circuit, and a relay included in both the local and loop circuits for sending signals.

4. In a telegraph system, a signaling path, a signal means associated with said signaling path and responsive to positive and negative impulses for repeating corresponding impulses to a local circuit, a control, a break and a pole-changing relay each having a winding included in said local circuit, a loop circuit, additional windings on the two last mentioned relays included in said loop circuit, said control relay being operated to open and close said loop circuit in accordance with the operation of said signal means, and means associated with said other relay for preventing its operation due to the opening of said loop circuit by said control relay.

5. In a telegraph system, a metallic line circuit, a local circuit, a vibrating relay connected in said line circuit and responsive to impulses of positive and negative polarity for repeating corresponding impulses to said local circuit, a plurality of relays each having a winding included in said local circuit, a loop circuit, additional winding on two of said relays connected in said loop circuit, one of said relays being operated to open and close said loop circuit, and means included in said local circuit for preventing the operation of the two relays which have windings connected in the loop circuit upon the reversal of said vibrating relay.

6. In a telegraph system, a metallic line circuit, a local circuit, a vibrating relay connected in said line circuit and responsive to impulses of positive and negative polarity for repeating corresponding impulses to said local circuit, a control, a break and a pole-changing relay each having a winding included in said local circuit, a loop circuit, additional windings on the two last mentioned relays connected in said loop circuit, means included in said local circuit for preventing the operation of said break and pole-changing relay on the reversal of said vibrating relay, a transmitting key connected in said loop circuit, and circuit connections effective upon the simultaneous operation of said key and the reversal of said vibrating relay for establishing the continuity of said loop circuit independent of said control relay.

7. In a telegraph system, a metallic line circuit, a local circuit, a vibrating relay con-

nected in said line circuit and responsive to impulses of positive and negative polarity for repeating corresponding impulses to said local circuit, a control, break and pole-changing relay each having a winding included in said local circuit, a loop circuit, additional windings on the two last mentioned relays connected in said loop circuit, means included in said local circuit for preventing the operation of said break and pole-changing relay on the reversal of said vi-

brating relay, a transmitting key connected in said loop circuit, and circuit connections effective upon the simultaneous operation of said key and the reversal of said vibrating relay for short circuiting the contacts of said control relay whereby the loop circuit is maintained closed. ¹⁵

In witness whereof, I hereunto subscribe my name this 25th day of June A. D., 1924.

GEORGE C. CUMMINGS.
